GRID STRUCTURE FOR ELECTRON
DISCHARGE TUBESWilliam H. Bussey, Chicago, Ill., assignor to
Robert L. Kahn, trustee, Glencoe, Ill.

Application May 17, 1947, Serial No. 748,811

8 Claims. (Cl. 250—27.5)

1

This invention relates to an electrical apparatus and particularly to an electrometer vacuum tube and vacuum-tube circuit for use in amplifying minute potentials of a direct or slowly varying nature generated by or associated with high impedance sources. Thus, the invention may be used in connection with measurements of extremely high resistances, measurements of hydrogen ion concentration and also in connection with potentials developed by photoelectric cells, ionization chambers and similar devices.

Conventional vacuum tubes, when operating on minute direct potentials, are limited and seriously handicapped by what might be termed the inherently "noisy" characteristics of a thermionic cathode. Such a cathode, when considered with respect to minute direct potentials is far from being stable or equi-potential. Such "noisy" characteristics involve drifts and the variation of electron emission with respect to time. The potential and electronic instability of a thermionic cathode, with reference to minute direct potentials, has been the subject of considerable research and discussion. As a result, vacuum tubes of the prior art and vacuum-tube circuits of the prior art have been limited as regards sensitivity by poor constant potential resolution of a thermionic cathode. It is evident that the lowest direct potentials upon which a vacuum tube may operate with any degree of reliability are limited by the magnitude of emission fluctuations present in thermionic cathodes. If such emission fluctuations can be effectively eliminated, it will follow that the lower limit of constant potentials to be amplified may be reduced to a lower order.

By virtue of the invention disclosed herein, there is provided a vacuum tube and circuit therefore capable of operating on substantially lower constant potentials than has hitherto been considered possible. A system embodying the present invention reduces the effective instability of a thermionic cathode to a lower order than is now possible.

The invention, in general, contemplates a vacuum tube having one physical cathode system and twin control and twin anode electrodes. The twin control electrodes and twin anode electrodes are electrically and geometrically twins as seen from the cathode. With respect to the cathode, the differences between each of the twin control electrodes and each of the twin anode electrodes is of a low order. As a result of such a twin system of control and anode electrodes, the single thermionic cathode may be resolved into twin groups of thermionic cathode elemental areas.

2

The two groups are completely intermingled so that any variation in emission from the single physical cathode may be considered as divided equally between the two groups. The cathode may either be an actual thermionic cathode constructed in a conventional manner or may consist of a conventional thermionic cathode having, in addition, a suitable ion-repelling electrode forming a virtual cathode for supplying electrons. Thus, twin tubes are provided, and the differences between them are of a lower order than hitherto considered possible.

In order that the invention may be fully understood, a description thereof will now be given in connection with the drawings wherein Figure 1 is a sectional elevation of one form of a vacuum tube embodying the present invention. Figure 2 is a sectional plan view taken along line 2—2 of Figure 1. Figure 3 is an elevation of the single ion control grid. Figure 4 is an elevation of one of the control electrodes. Figure 5 is a diagrammatic view of a circuit embodying the present invention and with which a tube shown in Figure 1 may be used.

A tube embodying the present invention may have a conventional base with contact pins. The tube proper has evacuated envelope 12 of glass. Envelope 12 has reentrant portion 13 terminating in press 14 upon which the electrode mount is supported.

The electrode mount may be conveniently designed as a complete unit in a manner generally resembling vacuum tubes now on the market. Thus, two mica discs 15 and 16 may be provided, these discs being suitably apertured to clear the various supporting rods and wires. The electrode mount has cathode 20 of any suitable construction. Preferably, cathode 20 is of the filamentary type and may consist of a wire of nickel, platinum or the like, having a surface coated with suitable compounds, generally a mixture of barium and strontium oxides. Such cathodes are of the Wehnelt type. However, the thoriated type of cathode may also be used, in which case wire 20 may be of tungsten or other suitable metal having a suitable quantity of thorium therein to provide for electron emission. Filament 20 passes through apertures in the mica discs and is tensioned at the top by spring 21. Leads 22 and 23 sealed in the press support the filament and provide a heating circuit.

Cathode 20 has disposed around it grid 25 for repelling ions. Such a grid may have impressed thereon a suitable bias, preferably positive with respect to the cathode. The grid may be omitted

if desired. Grid 25 is constructed in the usual manner and may consist of a simple coil of wire 26 carried by supporting posts 27 and 28 passing through the mica discs and anchored in press 14. Posts 27 and 28 have clips spot-welded thereto on opposite sides of the mica disc for support purposes. Such retaining means are well known in the tube art. The grid may consist of nickel or molybdenum, and the two posts may also be made of the same material. Other metals, such as tantalum, may be used. The actual construction of the grid and its attachment to the posts are well known in the art and may be accomplished in any one of a number of ways. The pitch of the wire coil, wire diameter and its proximity to cathode surface 20 are all matters well within the skill of those versed in the vacuum tube art. Post 28 is extended through press 14 for connection purposes.

The vacuum tube so far described is of conventional construction. In accordance with the invention, a pair of interleaved control electrodes 30 and 31 are provided. The interleaved electrodes may assume any one of several constructions, one of which may resemble the structure shown in Figure 4 and consist of wire rings attached to posts 32 and 33 for electrode 30 and to posts 34 and 35 for electrode 31. As shown in Figure 2, the ring supporting parts of posts 32 and 33 for one electrode are in a plane perpendicular to the plane of the ring supporting parts of posts 34 and 35 for the other electrode.

Posts 32 to 35 inclusive have their ends passing through the mica discs and have suitable means for maintaining them in position. Leads 36 and 37 are connected to the respective control electrodes and extend upwardly through the top of the tube.

As clearly indicated in Figure 1, rings of one control electrode 30 are interleaved with rings of other control electrode 31. Thus, a transverse view, as shown by Figure 1, discloses alternate rings of control electrodes 30 and 31 along the height of the mount. The spacing between adjacent rings of the two electrodes 30 and 31 is equal. Other electrode constructions as two helical coils forming a sort of double thread may be used. In general, the two electrodes should be as symmetrical as possible with respect to the electron stream. Thus, one ring of one electrode should be mid-way between the adjacent rings of the other electrode. It is preferred to have the electrodes extend well beyond the effective ends of the emitting part of the cathode so that, at the ends of the electrode structure, the electron stream is practically nothing. The size of wire, spacing between adjacent rings, diameter of the rings and the like are all matters well within the skill of a tube designer and will depend upon desired tube characteristics. In order for one series of wire rings to clear the supporting posts of the other series of rings, it is preferred to make the rings somewhat elliptical as shown. The actual manner in which the wire rings are carried by the supporting posts may be varied.

Extending beyond the two control electrodes are anodes 40 and 41. The anodes are constructed in substantially the same manner as the control electrodes with anode 40 consisting of a series of rings carried by posts 42 and 43. Anode 41 is carried by posts 44 and 45. The plane of the ring supporting portions of one set of posts is preferably at right angles to the plane of the ring supporting portions of the other sets of posts so that the two series of rings may be inter-

leaved. It is understood that all of the supporting posts for the control electrodes and anodes are suitably supported in the mica discs by clips on opposite sides of each disc or other means.

Leads 44 and 43 for connection to a source of potential are connected to the respective anodes. As with the rings on the control electrodes, rings 40 and 41 are flattened for post clearance.

While not essential, it is believed that best results will be obtained by having rings 40 and 41 match in number and spacing corresponding rings 30 and 31. Thus, looking at the tube from the side as seen in Figure 1, one ring of a control electrode is preferably in line with one ring of its associated anode. It is not necessary that the size of wire forming the anode rings be the same as the size of wire forming the control electrode rings. The diameter of the anode rings will be determined by considerations of tube characteristics. As shown in the drawing, supporting posts 42 and 43 carry rings 40, and these rings are preferably in line with rings 30 carried by posts 32 and 33. By proper shaping of the rings to avoid one pair of posts, it will be evident that symmetry for grids and anodes may be maintained.

It is desirable to enclose the entire mount in a shield to prevent electrons from drifting to the interior of the glass envelope and building up a charge. To this end, shield 46 is provided, this shield preferably though not necessarily having top and bottom parts 47. The shield may be made of any suitable metal and the top and bottom are suitably apertured to clear the various wires and supporting posts. The shield may be supported by wires 48 and 49 sealed in the press, wire 49 for example being extended for connection to a suitable source of constant potential, such as ground.

It is possible to obtain this shielding action by other means. Thus, a conducting metal coating of silver, magnesium or any other desired metal may be obtained on the inside of the glass envelope in a manner well known in the vacuum tube art. It is understood, of course, that such a conducting metal coating will be kept clear of the press and leads going through the glass except that one lead from the coating for connection to ground may be provided.

No attempt has been made to show dimensions and proportions of electrodes or electrode spacing. Such matters will vary with desired tube characteristics. In general, such matters are well within the skill of those working in the tube art.

Referring now to Figure 5, a circuit diagram of a differential amplifier in which the tube embodying the invention may be used is disclosed. The various tube electrodes are identified by the same numbers as used in the tube itself. Thus,

cathode 20 has one terminal connected to junction 50 and its other terminal connected to point 51. Between points 50 and 51 is resistor 52. Ion control grid 25 is connected to point 54. Between point 54 and 51 is resistor 55. Between point 54 and terminal 56 is resistor 57. Between point 50 and terminal 59 is resistor 58. Resistors 58, 52, 55 and 57 may all form part of a tapped voltage divider. Between terminals 56 and 59, battery 60 or other source of constant potential is connected, the polarity being such that terminal 56 is positive. It will be noted that shield 46 is connected to ground. In the event that a mirror surface on the inside of the glass envelope is used, then it will be understood that such mirror surface is also grounded. The

shield may be connected to any other point of constant potential.

Control grids 30 and 31 are connected to junctions 61 and 62 respectively, between which junctions high resistance 63 is connected. Resistance 63 may have any desired value and, in practice, may have values in the megohm range, such as ten, one hundred or even more megohms. However, such values are merely exemplary and any values necessary may be used. Resistance 10 15 63 has grounded tap 64 connected by lead 65 to terminal 59, the control grids being thereby negatively biased.

Junction 61 is connected by lead 66 to terminal 67. Between terminals 67 and 69 are connected in shunt source of constant potential here shown as battery 69 and potentiometer resistor 70. Wiper 71 cooperates with resistor 70, and the wiper is connected by lead to one terminal of source 72 whose potential is to be amplified. Source 72 has its other terminal connected by lead 73 to movable switch contact 74. Switch contact 74 cooperates with fixed contacts 75 and 76 connected to points 62 and 64 respectively.

The polarity of potential sources 69 and 72 is such as to provide opposition so wiper 71 may be adjusted for null operation. This will provide a high degree of sensitivity although source 72 may be connected directly across points 61 and 62 or across points 61 and 64 or across points 62 and 64. The polarity of sources 69 and 72 may both be reversed if desired. In any event, it will generally be desirable to have any possible potential across source 72 small in comparison to the normal negative bias of the control grids.

With switch contact 74 on 75 as shown, symmetrical operation is secured. However, contact 74 may be moved to 76, and the system will operate. In the event that one terminal of source 72 is grounded, then the optional switch position on 76 will be necessary. Whichever pole of source 72 is grounded, source 69 will be so poled as to oppose source 72.

For sensitivity, it is advisable to provide high order of insulation resistance to ground for those elements connected to junctions 61 and 62.

Anodes 40 and 41 are connected to junctions 80 and 81 respectively. Junctions 80 and 81 have connected across them load resistor 85. Resistor 85 has wiper 86 cooperating therewith, which wiper is connected to terminal 56. Wiper 86 is adapted to be manually adjusted to provide a normal no-load balanced tube condition. Under such condition, no difference in potential between terminals 61 and 62 should exist.

It should be noted that the output circuit of the amplifier resembles a bridge. Thus, resistor 85 forms two adjacent bridge arms with wiper 86 as a bridge point. Cathode to anode spaces form remaining adjacent bridge arms. Battery 60 is connected across one bridge diagonal from wiper 86 to cathode 20. Bridge output points 80 and 81 are across the other bridge diagonal.

Terminals 80 and 81 may be considered as the output terminals of the amplifier and may have connected across them any suitable load. Thus, for a direct reading system, any suitable meter may be connected. It is also possible to connect the output of this amplifier to an additional direct current amplifier which may, if desired, be similar to the amplifier system so far described. Such additional amplifier or a direct current power amplifier indicated by numeral 88 may feed any suitable load.

Thus, as an example, power amplifier 88 may

be connected to junction points 80 and 81 to be operated thereby. Such a power amplifier may be a conventional direct current amplifier for use with substantial potentials of the order of one-tenth volt or higher. Thus, amplifier 88, which may include as a part thereof a stage of amplification similar to the amplifier described in detail herein, may feed its output through leads 90 and 91. Such leads may feed indicating instrument 92, which may be either of the direct reading or recording type.

It is believed that sensitive operation of the amplifier embodying the present invention will be present if the amplifier is operated in the neighborhood of its balance point, i. e. with the control electrodes at the same instantaneous potential. Thus, in the event that a potential is to be amplified, it is possible to provide means for maintaining an opposing potential to balance control electrodes 30 and 31. Thus, leads 90 and 91 may feed servo motor 93 which is mechanically connected to move wiper 71. The system may be set up in such a manner that the polarity and difference of potential between leads 90 and 91 will serve to move wiper 71 and restore control electrodes 30 and 31 to a balanced potential condition. Scale 94 shows the position of wiper 71 and may be calibrated to read the potential due to source 72. The calibration may be in terms of temperature or other physical condition.

One battery or other source of constant potential may be used for energizing the vacuum tube. In practice, such a battery will generally have a low potential which may be of the order of about six volts. It is understood, however, that separate filament heating and plate supply batteries may be used. Other means for obtaining grid bias may also be used.

In order to utilize the full sensitivity of the system, it may be advisable to operate the cathode at temperatures far below that used in conventional vacuum tubes. The same applies to control electrode bias and anode potential. By virtue of the low potentials used, the possibilities of erratic behavior due to ion bombardment, secondary emission and ionization will be greatly reduced. For the sake of simplicity, a filamentary cathode has been disclosed. However, it is understood that this cathode may be replaced by an indirectly heated cathode. Other changes for adapting the tube or circuit to meet special conditions may be made as desired.

It will be apparent that a pair of twin control electrodes are provided having the effective portions thereof interleaved. When such interleaved portions are projected on the cathode surface, a symmetrical pattern will be formed, this pattern consisting of elements of the two control electrodes alternating with each other. Similarly, the anode electrodes have the effective portions thereof interleaved so that a projection from the two electrodes on the cathode will also provide an alternating symmetrical pattern. The alignment of the control electrode and anode interleaving portions is such that the projection on the cathode of the interleaving portions of one control electrode will coincide with the projection on the cathode of the interleaving portion of one anode electrode. The same applies to the remaining control and anode electrodes.

While it is preferred to have the physical structure of the anode electrodes similar to the control electrodes, this is not essential. Thus, two control electrodes of similar construction may have 75 interleaved portions as shown. Two anode elec-

trodes of different construction than the control electrodes but with the two anode electrodes having similar construction will have interleaved portions. In such case, alignment between elements of a control electrode and an anode electrode will not be possible. However, it will be possible to arrange the control electrodes and anode electrodes in such a manner that symmetry and correspondence will be obtained.

By virtue of the invention, a sort of push-pull action is obtained not only on the control electrodes but also with the anode electrodes. This push-pull action differs from a conventional push-pull amplifier in that the dissimilarity between one vacuum tube unit consisting of cathode, control electrode and anode, and the other vacuum tube unit consisting of the same cathode, remaining control electrode and remaining anode is reduced to a lower order than has hitherto been possible.

What is claimed is:

1. A vacuum tube comprising an evacuated envelope, a thermionic cathode, a pair of twin control electrodes, a pair of twin anode electrodes, the two twins of each pair having interleaved portions whereby a pair of twins are spatially displaced from each other to provide electrically distinct structures with the interleaved portions of a pair of twins forming a symmetrical pattern of alternating twin electrode portions when projected on the cathode.

2. The structure according to claim 1 wherein the twin control electrodes are similar to the twin anode electrodes and wherein the control and anode electrodes are aligned, the patterns formed by projection of the interleaved portions of the anode electrodes coinciding with the pattern formed by the projection of the control electrodes on the cathode.

3. A vacuum tube for use in a differential amplifier comprising a thermionic cathode, a pair of twin control electrodes surrounding said cathode, said control electrodes having substantial portions thereof interleaved with each other, said twin control electrodes being electrically distinct but symmetrically disposed with respect to each other, so that interleaved portions of said control electrodes when projected on the cathode form a symmetrical pattern of alternating twin electrode portions, a pair of twin anode electrodes surrounding said control electrodes and having substantial portions thereof interleaved, said anode electrodes being electrically distinct but symmetrically disposed with respect to each other, interleaved portions of the anode electrodes when projected on the cathode forming a symmetrical pattern of alternating twin electrode portions, said cathode, control electrodes and anode electrodes together forming two vacuum tube units having a common cathode and individual control and anode electrodes with the order of operating dissimilarity

between said units being substantially lower than between units having individual cathodes.

4. The structure according to claim 3 wherein the control electrodes and anode electrodes are similar to each other in construction and have their interleaved portions aligned so that the projected patterns on the cathode of the anode electrodes coincide with the projected pattern of the control electrodes on the cathode.

5. A vacuum tube for use in a differential amplifier comprising a thermionic cathode, an ion control grid disposed around said cathode, a pair of twin control electrodes surrounding said ion control electrode, said control electrodes having substantial portions thereof interleaved with each other, said control electrodes being electrically distinct and symmetrically disposed with respect to each other, said interleaved portions when projected on the cathode forming a symmetrical pattern of alternating twin electrode portions, a pair of twin anode electrodes surrounding said control electrodes and having substantial portions thereof interleaved, said anode electrodes being electrically distinct and being symmetrically disposed

15 with respect to each other, said interleaved portions when projected on the cathode forming a symmetrical pattern of alternate twin electrode portions, the anode and control electrode portions being aligned, the pattern for the control electrode

20 overlaying the pattern for the anode electrodes, said structure forming two vacuum tube units having a common cathode and ion control electrode but individual control and anode electrodes with the two units having a substantially lower order

25 of operating dissimilarity between them than possible with units having individual cathodes.

20. 5. A vacuum tube for use in a differential amplifier comprising a thermionic cathode, an ion control grid disposed around said cathode, a pair of twin control electrodes surrounding said ion control electrode, said control electrodes having substantial portions thereof interleaved with each other, said control electrodes being electrically distinct and being symmetrically disposed with respect to each other, said interleaved portions when projected on the cathode forming a symmetrical pattern of alternating twin electrode portions, a pair of twin anode electrodes surrounding said control electrodes and having substantial portions thereof interleaved, said anode electrodes being electrically distinct and being symmetrically disposed

30 with respect to each other, said interleaved portions when projected on the cathode forming a symmetrical pattern of alternate twin electrode portions, the anode and control electrode portions being aligned, the pattern for the control electrode

35 overlaying the pattern for the anode electrodes, said structure forming two vacuum tube units having a common cathode and ion control electrode but individual control and anode electrodes with the two units having a substantially lower order

40 of operating dissimilarity between them than possible with units having individual cathodes.

6. The structure of claim 5 wherein a shield around the anodes is provided.

7. The structure of claim 3 wherein each of the

45 control grids comprises a pair of supporting posts

and a series of rings carried thereby, the rings for

the one control grid clearing the supporting posts for

the twin control electrode.

8. The structure according to claim 3 wherein each of the twin electrodes comprises a pair of supporting posts and a series of metal rings, the rings for one of the twins being interleaved with

the rings of the other twin and clearing the posts of the other twin.

50 WILLIAM H. BUSSEY.
